GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID-PRESSURE MOTOR

Application filed January 17, 1927. Serial No. 161,479.

This invention relates to fluid pressure motors, machines and tools in which a piston is reciprocated with a percussive effect. It is particularly adapted and intended for use in fluid pressure percussive machines in which the piston is caused to rotate as well as to reciprocate, the rotative movement as well as the percussive movement being imparted to a working tool in direct contact with the work.

In machines of the type described, such for example as pneumatic rock drills, the speed or the number of blows per minute depends upon the total weight of the reciprocating piston, other factors remaining the same. It is accordingly an object of the invention to increase the operating efficiency of such tools by increasing the speed thereof, this result being secured by reducing the weight of the piston. Another object of the invention is to reduce the piston weight without increasing the clearance space for the motive fluid in the piston chamber and without interfering with the renewing of parts of the rotative mechanism. Other objects will be apparent from the detailed description which follows.

In order to illustrate the invention one concrete embodiment thereof is disclosed in the accompanying drawings in which:

Fig. 1 is a longitudinal vertical sectional view through a rock drill having a piston of the improved type;

Fig. 2 is an enlarged elevational view partly in section of the piston shown in Fig. 1; and,

Fig. 3 is a top plan view of the piston shown in Fig. 2.

Fig. 1 discloses a fluid pressure percussive machine commonly referred to as a rock drill comprising a cylinder 4 having a back head 5 and a front head 6 secured thereto in any suitable manner as by through bolts (not shown). The cylinder provides a piston chamber in which reciprocates a hammer piston 7, the latter being driven by motive fluid admitted to the machine by a manually operated throttle valve 8, the motive fluid being distributed and controlled by an automatic valve (not shown) oper-

ating in timed relation with the movements of piston 7. The piston imparts its blows to a working tool or drill steel 9 having its shank end supported in a rotatable chuck member 10 in front head 6. During its reciprocations piston 7 is caused to rotate by mechanism of any known or desired type. In the present instance this mechanism comprises a rifle bar 11 rotatably supported together with its ratchet and pawl device 55 by back head 5 and cylinder ring 12, the rifle bar extending into the piston chamber and arranged to be received in a recess 7^a in piston 7. The rifle bar cooperates with a rifle nut 13 carried by piston 7 and the 60 rotative impulse transmitted to the piston by the rotation mechanism is in turn transmitted by the piston through ribs 7^b on the forward extension of the latter to a co-operating sleeve member 14 which is in turn 65 keyed to chuck 10. A tube 15 may be arranged to extend axially through the rifle bar 11 and piston 7 as shown to direct 70 cleansing fluid into the hollow bore of the drill steel 9.

The machine as so far described differs in no particular respect from established practice. Attention is now directed to the construction of the piston 7 to which the invention particularly relates. The piston as 75 shown in the drawing and as previously described is hollowed out at its rearward end to form a recess 7^c for the rifle bar 11 and this recess is enlarged adjacent the head of the piston by a counterbore 7^d which may 80 be interiorly threaded or otherwise arranged to have secured therein an insert member 16. This insert member enables the speed of the machine to be varied and since the speed will be increased by lightening 85 the weight of the piston, member 16 is preferably of some material lighter than the steel of which the piston proper is ordinarily constructed. Member 16 is of fabricated material commonly called fiber. Such material, which is both tough and resilient, is commercially available in various forms and under various trade names. One of the materials which has been found to be very satisfactory in service is known as "Mi- 90

95 Mi- 100

carta". Other materials which might be used are wood, rubber, and rubber compounds, also certain lighter metals such as aluminum or aluminum alloy.

6 Insert 16 supports rifle nut 13 as shown and may serve to at least partially relieve the latter of the shocks which occur at the reversal of the movement of the piston at the end of its stroke in both directions. To 10 this end the insert may be wholly or in part of resilient material. It is preferable to secure this effect by the use of a solid insert having resilient properties such as the fiber referred to above as the preferred material 15 or a vulcanized rubber compound. The connection between the insert and the piston on the one hand and between the insert and the rifle nut on the other may be made in any suitable or desired manner, the screw threaded connection being shown merely by way 20 of illustration. With a threaded connection the direction and pitch of the thread will be such as to cause the tightening of both the insert 16 and the rifle nut 13, when the rifle 25 bar is held by the ratchet and pawl mechanism against rotation,—i. e. when the rotation mechanism is effective to impart a rotative impulse to the piston as on the back stroke of the piston in the drill shown in 30 Fig. 1.

From the above it will be apparent that the present invention provides for increasing the speed of a fluid pressure motor of the described type by lightening the piston 35 to any desired extent, that the insert provided for this purpose need not increase the clearance space in the piston chamber so as to waste motive fluid or impair the operating characteristics of the motor, that the 40 insert may serve as a resilient support for one of the parts of the rotation mechanism so as to at least partly relieve this mechanism of shock, that the bearing surfaces of the piston and the rotation mechanism are 45 not reduced, and that renewal of worn parts is not prevented or made difficult.

While a preferred form of the invention has been herein shown and described, it is to be understood that the invention is not 50 limited to the specific details thereof but covers all changes, modifications and adaptations within the scope of the appended claims.

I claim as my invention:

- 55 1. A fluid pressure motor comprising a cylinder providing a piston chamber, a piston reciprocable therein, rotative mechanism for said piston including a rifle nut on said piston and a rifle bar projecting 60 within said cylinder, said piston having a recess to receive said rifle bar, and an insert at least partly within said recess and of lighter material than said piston for resiliently supporting said rifle nut.
- 65 2. A piston for a fluid pressure motor

comprising a metallic member having a recess at one end, an insert of resilient non-metallic material extending within said recess and having an axial bore, and a rifle nut supported by said insert within said bore.

Signed by me at Detroit, in the county of Wayne, State of Michigan, this 13th day of January, 1927.

CERTIFICATE OF CORRECTION.

Patent No. 1,769,034.

Granted July 1, 1930, to

GUSTAVE M. NELL.

It is hereby certified that error appears in the printed specification of the above numbered patent requiring correction as follows: Page 2, line 68, claim 2, after the word "material" insert the words lighter than the material of said metallic member; and that the said Letters Patent should be read with this correction therein that the same may conform to the record of the case in the Patent Office.

Signed and sealed this 5th day of August, A. D. 1930.

(Seal)

Wm. A. Kinnan,
Acting Commissioner of Patents.
